BUFFER

Louis A. Anderson, Dayton, Ohio, assignor to
 General Motors Corporation, Dayton, Ohio, a
 corporation of Delaware

Application August 26, 1943, Serial No. 500,162

2 Claims. (Cl. 267—1)

1

This invention relates to a buffer and more particularly to a barrel buffer for use on a 50 caliber Browning machine gun.

At present, the 50 caliber Browning machine gun is provided with a barrel buffer wherein the buffering action is produced by a plunger moving through a body of oil. In such an arrangement, the temperature materially affects the rate of fire of the gun and it frequently happens that some or all of the oil leaks out with the result that the buffer is none too dependable.

A large number of buffer designs have been proposed in an effort to eliminate the need for the use of oil in the buffer, but these have proven unsatisfactory for various reasons. Some have increased the load on the back plate too much or have decreased the rate of fire. Others have interfered with the hand cocking of the gun or have been impractical for other reasons. It is an object of this invention to provide a practical buffer which does not have any of the above mentioned disadvantages.

Thus one object of this invention is to provide a buffer which is operable at all temperatures and elevations normally encountered.

Another object is to provide an improved barrel buffer which is completely interchangeable with the present oil buffers now in use on 50 caliber machine guns.

Further objects and advantages of the present invention will be apparent from the following description, reference being had to the accompanying drawings, wherein a preferred form of the present invention is clearly shown.

In the drawings:

Fig. 1 is a fragmentary elevational view with parts broken away showing somewhat diagrammatically a standard machine gun provided with my improved barrel buffer;

Fig. 2 is a longitudinal sectional view through my improved barrel buffer;

Fig. 3 is a view similar to Fig. 2 showing the position of the parts when the barrel extension has moved to its rearmost position;

Fig. 4 is a cross sectional view taken on line 4—4 of Fig. 3; and

Fig. 5 is a fragmentary sectional view of a buffer showing a slightly modified type of brake shoe.

Referring now to Fig. 1 of the drawings, reference numeral 10 designates generally the breech housing of a standard 50 caliber Browning machine gun. Reference numeral 12 designates the barrel of the gun and reference numeral 14 designates the barrel extension which is normal-

ly movable along with the barrel 12 upon recoil. The barrel extension 14 is provided with a projection 15 which interlocks with the buffer mechanism generally designated by the reference numeral 20. The barrel buffer 20 is supported by the stationary element 22, the construction of which is the same as now used with the oil buffer on a standard gun. The outer shape and size of the barrel buffer 20 is similar to the shape and size of the present oil type buffer and is completely interchangeable therewith without modifying any of the other gun parts.

Reference numeral 24 designates a conventional bolt buffer carried by the end plate 16 in accordance with standard practice. The bolt buffer may be of the fiber disc type now used or it may be of any other construction suitable for stopping the movement of the bolt.

Referring now to Fig. 2 in which there is shown a sectional view of my improved buffer construction, reference numeral 30 designates the main buffer cylinder which is made of steel and within which a plurality of cast iron brake shoes 32 are adapted to reciprocate. A plunger 34 provided with a notch 36 at its forward end is adapted to interlock with the barrel extension element 15 as shown in Fig. 1. Upon recoil of the gun barrel the plunger 34 is moved to the rear. A cam element or wedge means 38 provided with a cam surface inclined 10° with respect to the plunger 34 is slidably mounted on the plunger 34 as shown. Upon recoil of the barrel, movement of the plunger 34 causes the cam element 38 to cam the brake shoes 32 into braking engagement with the inner wall of the cylinder 30. A spring 40 surrounding the shank of the plunger 34 has its one end in engagement with the cam 38 and has its other end arranged in engagement with the element 42 which abuts against the enlarged portion 44 of the plunger 34. When the plunger 34 is first moved to the rear, the cam 38 pushes the shoes 32 outwardly. The outward pressure of the shoes is determined by the amount the spring 40 is compressed. The maximum pressure is exerted by the spring 40 when the ends 46 of the shoes are struck by the element 42. When the forward ends 46 become engaged by the element 42, the shoes are forced to move in unison with the plunger 34 without any further increase in pressure.

By virtue of this construction the spring 40 alone opposes the recoil of the barrel and barrel extension at the beginning of the recoil movement and then when the plunger 34 has moved far enough so that the brake shoes have been

cammed outwardly, the brake shoes afford increased resistance to the movement of the barrel and barrel extension. The arrangement is such that upon slow movement of the plunger 34, such as is produced upon hand cocking of the gun, the brake shoes 32 move to the rear without being cammed outwardly. However, the inertia of the brake shoes is sufficient that upon very rapid movement of the plunger 34, the cam 38 first cams the shoes into braking engagement before the shoes have moved any appreciable distance toward the rear.

A coil spring 48 is arranged between the forward end wall 31 of the cylinder 30 and the guide washer 50. A pin 52 assists the spring 48 in holding the guide washer 50 in proper assembled relationship on the plunger 34. Suitable lugs 54 are provided on the guide washer 50 so as to prevent rotation of the guide washer relative to the plunger. The washer 50 is provided with a side lug 51 which is adapted to engage in a slot (not shown) in the side wall of the element 22. The construction of the washer element 50 is the same as now used on the oil buffer and needs no further description. A flanged nut 56 is threaded onto the inner end 58 of the plunger 34. The nut 56 serves as an abutment for the cam element 38 and also has a flange which serves as an abutment for the brake shoes 32 as the plunger 34 moves forward. The nut 56 contacts the brake shoes 32 when the apparatus is at rest, as shown in Fig. 2, and when the plunger 34 is moving from its rear position to its forward position.

For purposes of illustration, I have shown five brake shoe segments, whereas it is obvious that the number of brake shoe segments may be varied. An uneven number of brake shoes is preferable so as to avoid having two opposed shoes assuming the full load. The clearance between the brake shoe segments is enough so that the plunger together with the brake shoes does not serve as a fluid tight piston assembly. The rear end of the cylinder 30 is closed by means of the element 33 which is threaded onto the cylinder 30 as shown. A clearance recess 60 is provided in the element 33 so as to allow the plunger 34 to move to the rear of the cylinder 30.

In Fig. 5 I have shown a modified buffer arrangement in which the brake elements are provided with inserts 70 of brake lining material. In this modification, ball bearings 72 have been provided between the cam 38 and the brake shoes 32. The purpose of this ball bearing arrangement is to reduce the amount of friction between the cam 38 and the inclined surface of the shoe 32 so that the cam will have a better chance to cam the shoes into braking engagement before the shoes begin moving longitudinally within the cylinder 30.

The ball bearings 72 roll within the race 74 which is long enough to allow the ball bearings to roll lengthwise therein during the camming action. The pin 76 returns the ball bearings to the front end of the race after each operation. Thus, as the plunger 34 moves forward, the nut 56 pushes the pin 76 inwardly so as to push the ball bearings to the front end of the slot. Upon recoil of the gun, the plunger 34 pushes the nut 56 away from the rear end of the brake shoes so that the ball bearings and the pin 76 are free to move as they please.

While I have shown the buffer used as a barrel buffer in a 50 caliber Browning machine gun, it is obvious that it could be used in other kinds of

guns and in other apparatus where buffer action is required.

A buffer of the type described hereinabove has the advantage that it does not vary in operation upon changes in temperature and elevation. Once the buffer leaves the factory it requires no further adjustment and is completely interchangeable with the existing oil buffers now in use. Furthermore, the buffer does not materially interfere with hand cocking of the gun since the brake shoes move along with the plunger out of contact with the cylinder wall when the plunger moves slowly.

While the form of embodiment of the invention as herein disclosed constitutes a preferred form, it is to be understood that other forms might be adopted, as may come within the scope of the claims which follow.

What is claimed is as follows:

1. In a buffer, a hollow cylinder; said cylinder having an opening provided in the one end thereof; said one end having a projecting cylindrical portion of smaller outer diameter than the main cylinder and connected to the main cylinder by a flange which forms an external spring seat and an internal stop surface; piston means operable within said cylinder comprising a plurality of brake shoe segments having portions disposed within said hollow cylinder and having internal wedge surfaces; a plunger having a portion disposed substantially centrally within said cylinder and surrounded by said brake shoe segments, and wedge means slidably mounted on said plunger for wedging said brake shoe segments into braking engagement with the wall of said cylinder upon rapid movement of said plunger in one direction; a shoulder on said wedge means; a shoulder on said plunger; a spring surrounded by said brake shoe segments and engaging said shoulders for biasing said wedge means into engagement with said internal wedge surfaces; and a coil spring surrounding said plunger and said projecting cylinder portion and having one end in engagement with said plunger and having its other end in engagement with said spring seat for biasing said plunger outwardly of said hollow cylinder; said brake shoe segments having stop surfaces for engagement with said internal stop surface for limiting the movement of said segments and having portions extending outwardly of said cylinder and disposed between said first and second named springs so as to form a barrier between said springs.

2. In a buffer, a hollow cylinder; said cylinder having an opening provided in the one end thereof; said one end having a projecting cylindrical portion of smaller outer diameter than the main cylinder and connected to the main cylinder by a flange which forms an external spring seat and an internal stop surface; piston means operable within said cylinder comprising a plurality of brake shoe segments having portions disposed within said hollow cylinder and having internal wedge surfaces; said brake shoe segments having stop surfaces for engagement with said internal stop surfaces for limiting the movement of said brake shoe segments in one direction; a plunger having a portion disposed substantially centrally within said cylinder and surrounded by said brake shoe segments, and wedge means slidably mounted on said plunger for wedging said brake shoe segments into braking engagement with the wall of said cylinder upon rapid movement of said plunger in one direction; a shoulder on said wedge means; a shoulder on said plunger; a spring sur-

rounded by said brake shoe segments and engaging said shoulders for biasing said wedge means into engagement with said internal wedge surfaces; and a coil spring surrounding said plunger and said projecting cylinder portion and having one end in engagement with said plunger and having its other end in engagement with said spring seat for biasing said plunger outwardly of said hollow cylinder; said coil spring having an outer diameter substantially equal to the outer diameter of said hollow cylinder.
